(57) **CLAIM**

The ornamental design for a candle with crystal-shaped wax, as shown and described.

DESCRIPTION

FIG. 1 is a front perspective view of the candle with crystal-shaped wax, showing our new design;

FIG. 2 is another front perspective view thereof, with portions of a disclaimed candle container broken away for clarity of disclosure;

FIG. 3 is front elevation view thereof, with portions of the disclaimed candle container broken away for clarity of disclosure;

FIG. 4 is a rear elevation view thereof, with portions of the disclaimed candle container broken away for clarity of disclosure;

FIG. 5 is a left side elevation view thereof, with portions of the disclaimed candle container broken away for clarity of disclosure;

FIG. 6 is a right side elevation view thereof, with portions of the disclaimed candle container broken away for clarity of disclosure;

FIG. 7 is a top plan view thereof; and,

FIG. 8 is a bottom plan view thereof.

The evenly-sized broken lines shown in the drawings depict a candle container and portions of the wax that form no part of the claimed design.

The unevenly-sized broken lines define the bounds of the claimed design and form no part of the claimed design.

Any portion of the design not shown in the drawings forms no part of the claimed design and is hereby disclaimed.
